Oscar O. A. Grundstrom, Rockford, Ill.

Application November 30, 1944, Serial No. 116,627

Term of patent 14 years

(Cl. D93—4)

To all whom it may concern:

Be it known that I, Oscar O. A. Grundstrom, a citizen of the United States, residing at Rockford, in the county of Winnebago and State of Illinois, have invented a new, original, and ornamental Design for Hammer Head, of which the following is a specification, reference being had to the accompanying drawing, forming part thereof.

In the drawing:

Figs. 1 and 2 are, respectively, a top view and side view of a hammer head showing my new design, and

Fig. 3 is a perspective view of said hammer head.

I claim:

The ornamental design for a hammer head, as shown.

OSCAR O. A. GRUNDSTROM.
